Primary Examiner — Janice Hallmark(57) **CLAIM**

The ornamental design for a mobile phone case with a holder, as shown and described.

DESCRIPTION

1. Mobile phone case with a holder

1.1 : Perspective

1.2 : Front

1.3 : Back

1.4 : Left

1.5 : Right

1.6 : Top

1.7 : Bottom

1.8 : Exploded

This article is a mobile phone case with a holder on the back side of the case; the part to be protected is displayed as a solid line and the part to be unprotected is displayed as a dotted line; also, a boundary between the part to be protected and the part to be unprotected is displayed as an alternated long and short dash line.

1 Claim, 8 Drawing Sheets---
